Inventor:

DeWitt C. Beamer

United States Patent Office.

DE WITT C. BEAMER, OF PHILADELPHIA, PENNSYLVANIA, ASSIGNOR TO
HIMSELF AND JAMES MARKLAND, OF SAME PLACE.

Letters Patent No. 68,339, dated September 3, 1867.

BUSINESS CARD AND PIN-CUSHION.

The Schedule referred to in these Letters Patent and making part of the same.

TO ALL WHOM IT MAY CONCERN:

Be it known that I, DE WITT C. BEAMER, of the city and county of Philadelphia, and State of Pennsylvania, have invented a new and useful Combined Hermetically Sealed Perfumed Business Card and Pin-Cushion; and I do hereby declare that the following is a full and exact description thereof, reference being had to the accompanying drawings, and to the letters of reference marked thereon.

The nature of my invention consists of a double thickness business card, which contains between its folds a pin-cushion that has in its central part a hole filled with a perfume material for scenting the reverse side of the card. The combined card and pin-cushion will be understood by the following description. In the accompanying drawings, which make a part of this specification—

Figures 1 and 2 are a face and edge view of a piece of straw board, A, of the right dimensions to form a card when folded. It has a hole, *a*, for the scent to pass out and through the cover of the reverse side of the card.

Figures 3 and 4 are like views of the same piece, with a piece of lapping, B, opposite the hole *a*, there being a hole, *a'*, in said piece, which is filled with a perfume material, C.

Figure 5 is a view of the piece A, folded together and connected at its open edges by means of the strips D E.

Figure 6 is a face view of the business side of the card.

Figure 7 is a face view of the scented side of the same.

Like letters in all the figures indicate the same parts.

I construct the article in the following manner: By means of dies, or otherwise, I cut straw boards into pieces A, as represented in figs. 1 and 2. Each piece is of proper dimensions to form a card when folded at the red line *x x*. The hole *a* is to permit the scent escaping through the cover at the reverse side of the card, as hereinafter described. Opposite the hole *a* I paste a piece of lapping, B, as seen in figs. 3 and 4, the edges *b b*, leaving margins *c c*, so as to form spaces for pins to pass through, so that their points only may enter the lapping, as described hereafter. There is a hole, *a'*, in the piece B, which, when the piece A is folded, coincides with the hole *a*. Before folding said piece A, I fill the hole *a'* with a perfume material, C, and cover it with a thin piece of cotton wadding, C', or other suitable material, seen in fig. 5, which shows the board folded and connected at its open edge *d* by means of a strip of paper, D, pasted over it. There are strips of muslin E E pasted over the end edges, through which pins are stuck, and enter the edges of the lapping B. These strips E and the lapping B constitute the pin-cushion. The article is now ready to receive its cover F, which I paste on, as seen in figs. 6 and 7; the former showing the business face of the card, and the latter the perfumed face.

What I claim as my invention, and desire to secure by Letters Patent, is—

1. A combined hermetically sealed, scented, perfumed business card and pin-cushion, constructed substantially as above described, and for the purposes set forth.

2. The combination of the piece of lapping B with the board A and strips E E, the lapping having a hole, *a'*, for the reception of a perfume material, and being arranged substantially as described and for the purposes set forth.

In testimony that the above is my invention I have hereunto set my hand and seal this twenty-ninth day of June, 1867.

DE WITT C. BEAMER. [L. S.]
